UNITED STATES PATENT OFFICE.

THEODORE MILLER, OF DETROIT, MICHIGAN.

DESIGN FOR A STOVE.

SPECIFICATION forming part of Design No. 23,429, dated July 3, 1894.

Application filed April 5, 1894. Serial No. 506,504. Term of patent 7 years.

To all whom it may concern:

Be it known that I, THEODORE MILLER, a citizen of the United States, residing at Detroit, county of Wayne, State of Michigan, have invented and produced a new and original Design for Stoves; and I declare the following to be a full, clear, and exact description of the same, reference being had to the accompanying drawing, which shows a part thereof.

The drawing is a perspective showing a stove made in accordance with my design.

The leading features of my design consist of the ornamental base, a cylindrical drum, 5 an ornamental rim at the base of the drum, ornamental arms supporting the drum above the leg frame, and a dome shaped top.

A represents an annular base or leg frame ornamented with scroll-work. The legs A' 10 are ornamented on their front surfaces with scroll work and with rosettes, as at "a," toward their upper ends where the legs join the leg frame.

C is a cylindrical drum, the base of which 5 is formed with an annular ornamented rim C'. Rising from the leg frame are sup-

porting arms D curved vertically and ornamented with scroll-work and with a rosette toward the lower end thereof, as shown at "d." The rim C' at the base of the cylindrical 30 drum C rests upon the upper ends of the arms D, said arms as well as the legs being three in number, leaving an open space between the leg frame and rim. The lower end of the cylindrical drum C is ornamented with frame 35 work C² in relief, and the upper end of said drum is ornamented with a figure consisting of open work cut through the body of the drum as indicated at C³.

D² is a dome shaped top, formed with an ornamental rim D' at its base, the dome being formed with open work above the rim as indicated at "d." Above the dome is an urn E.

What I claim as my invention is—

The design for a stove substantially as 45 herein shown and described.

In testimony whereof I sign this specification in the presence of two witnesses.

THEODORE MILLER.
